UNITED STATES PATENT OFFICE

1,953,816

INCLOSED INDIRECT LIGHTING FIXTURE

Shirley R. Naysmith, Meriden, Conn., assignor to
The Miller Company, Meriden, Conn., a corpora-
tion of Connecticut

Application October 23, 1931, Serial No. 570,525

24 Claims. (Cl. 240—78)

The present invention relates to inclosed indirect lighting fixtures and is more especially designed to provide such fixtures capable of efficiently employing large lamp bulbs. It is designed to give an extensive, upward direction of light with or without a dimly illuminated lower translucent bowl. It is also so designed that the lamp bulb is screened from ordinary angles of vision so as not to produce glare.

10 The present invention contemplates an inclosed lighting unit preferably having a light transmitting cover member, a lower ornamental cover member which may be opaque or diffusing and which gives the fixture its ornamental appearance, and interposed between these two is a reflector generally of unornamental appearance but designed for proper light control.

15 The lighting unit is designed so that the lower ornamental cover member and reflector are detachable from underneath to give access to the lamp bulb for bulb renewal.

20 In order to completely enclose the unit, the glass cover member is designed so that its outer edge engages one of the lower members.

25 The accompanying drawing shows, for purposes of illustrating the present invention, several embodiments in which the invention may take form, it being understood that the drawing is illustrative of the invention rather than limiting 30 the same. In the drawing:

Fig. 1 is an elevational view with parts in section showing one form of an enclosed lighting unit designed for totally indirect lighting;

Fig. 2 is a fragmentary sectional view with parts 35 omitted and taken on the line 2—2 of Fig. 1;

Fig. 3 is a view similar to Fig. 1 showing a modified form of construction for obtaining a small amount of downwardly diffused light;

Fig. 4 is a sectional view on the line 4—4 of Fig. 40 3 on an enlarged scale;

Fig. 5 is a sectional view showing a further modified form of construction; and

Fig. 6 is a fragmentary detail.

A pendant lamp socket 10 supports a lamp bulb 11 as usual. The lamp socket is inclosed in a socket cover 12 which supports three screws indicated at 13. These screws support a ring-like member 14 carried inside the socket cover and large enough to admit the neck of the lamp bulb.

50 This ring-like member may be a sheet metal stamping or spinning and is drawn outwardly at its lower edge as indicated at 15 so as to receive and support the translucent glass cover plate 16 of 55 a comparatively large diameter and having its

lower edge extending downwardly as indicated at 17.

The ring 14 also carries two sheet metal straps 18 and 19 which may be riveted to it as indicated at 20. The lower ends of these frame members 60 18 and 19 carry links 21 and 22 and these links support a U-shaped strap 23 twisted as indicated. This strap is somewhat larger than the diameter of the lamp bulb 11 so that the frame is able to receive the largest size lamp bulb for which the 65 unit is designed. The strap 23 is secured to a turning 24 by screws indicated at 25. This turning is threaded as indicated at 26 and carries a downwardly extending stem 27 which may be in the form of a nipple. The links 21 and 22 permit 70 swinging the strap 23 and stem to one side as indicated in dot and dash lines in Fig. 2 so that the bulb may be removed or inserted.

The sheet metal reflector 30 has a central opening to receive the upper end of the turning 24 75 and is clamped against the strap 23 by a threaded ring 31. This reflector has a central substantially spherical portion 32 and an outer peripheral portion 33 which is of shallow dished shape as indicated. The outer edge 34 of the reflector is adjacent the lower edge 17 of the glass cover plate.

It will be seen that the reflector and cover plate afford widespread upward illumination, the paths of the rays being as indicated in the light lines 80 in the drawing.

85 The shape given the reflector 30 is not ornamental and in order to provide an ornamental unit a lower mask or cover member 35 is furnished. This cover member may be made of sheet metal and is held in place by a knob 36 90 threaded on the lower end of the stem 27. The lower cover member extends upwardly and may touch the outer edge of the reflector so as to assist in aligning it. It may also carry a felt ring 37 which acts as a gasket between the lower cover member and the upper glass cover, the outer edge 38 of the mask extends above the glass cover 17 so as to screen this glass against vision at ordinary angles.

95 In the form shown in Figs. 3 and 4, the upper glass cover 16 and the upper parts of the frame 18 and 19 are the same. Here the links 21 and 22 support a U-shaped strap 40 which in turn carries a depending nipple or stem 41. The nipple 100 and strap are secured together by a pin 42.

A sleeve 43 is slidably received on the lower part of the nipple 41. This sleeve permanently carries a small reflector stamping 44 and is threaded at its lower end as indicated at 45 to re- 105

ceive a locking ring 46. This locking ring is adapted to clamp an ornamental stamping 47 against the bottom of a diffusing glass bowl 48 which forms the lower ornamental part of the 5 lighting unit. This bowl is apertured as indicated at 49 to receive the sleeve and the bowl and fittings may be removably supported on the stem 41 by a knob indicated at 50.

The upper edge 51 of the diffusing glass bowl 48 10 supports a sheet metal stamping or spinning 52. This sheet metal part has a central spherical portion 53 and an outer shallow dished reflecting portion 54 similar to the parts 32 and 33 shown in Fig. 1. The stamping extends upwardly and outwardly from the outer edge of the glass bowl and receives the lower edge 17 of the glass cover member, a felt gasket 55 being interposed. The outer portion 56 of the stamping or spinning 52 masks the glass cover 16.

20 The reflector stamping has a central opening 57 to permit a small amount of light to pass downwardly where it strikes the reflector 44 and is scattered thereby to illuminate the lower diffusing bowl 48.

25 Figs. 5 and 6 show the frame members 18' and 19' in the form of resilient lengths of wire secured to the ring 14. The lower ends of these wire frame members are provided with collars 60 which are adapted to pass through large holes 30 61 in a reflector stamping 30', similar to the corresponding part in Fig. 1. The wires spring outwardly and enter the small parts 62 of these slots and support the stamping 30' in place. When the frame members 18' and 19' are squeezed 35 toward one another slightly, one can release the stamping from either one or both of the frame members. If it is removed from only one frame member, it may hang down as indicated in the dotted line position so as to give access to the lamp 40 bulb. Its upper edge passes inside the cover plate 16 as indicated. The center of the reflector stamping 39' carries a depending stem 63 which may support the lower cover member.

45 At the left side of the figure the diffusing bowl 48 is indicated in full lines. It supports a spinning or stamping 52', 56' having the shape indicated. This stamping may extend in and engage the stamping 30' to align it. The stamping 30' is perforated as indicated at 64 to permit light 50 to pass downwardly for illuminating the diffusing bowl 48.

55 At the right hand side of Fig. 5, the sheet metal mask 35 is indicated in dot and dash lines.

50 It is obvious that the invention may be embodied in many forms and constructions, and I wish it to be understood that the particular forms shown are but a few of the many forms. Various modifications and changes being possible, I 60 do not otherwise limit myself in any way with respect thereto.

What is claimed is:

1. An inclosed indirect lighting unit, comprising a pendant lamp bulb, a pendant axially disposed stem below the lamp bulb, an ornamental cover member removably secured to the stem, an outwardly and upwardly flaring reflector disposed between the lamp bulb and the lower cover member which conceals the reflector and provides the 65 unit with its lower ornamental appearance, an inverted dished translucent cover plate above the lamp and reflector and engaging at its periphery one of said lower parts to form a closed body about the lamp bulb and transmit direct light 70 and reflected light upwardly, one of said lower 75

parts having an upwardly and outwardly flaring portion beyond the periphery of the cover plate for screening the cover plate at angles below the horizontal, and means for supporting the stem and cover plate in position relative to the lamp 80 bulb.

2. An inclosed indirect lighting unit, comprising a pendant lamp bulb, a pendant axially disposed stem below the lamp bulb, an ornamental cover member removably secured to the stem, an outwardly and upwardly flaring reflector disposed between the lamp bulb and the lower cover member which conceals the reflector and provides the unit with its lower ornamental appearance, an inverted dished translucent cover plate above the lamp and reflector and engaging at its periphery one of said lower parts to form a closed body about the lamp bulb and transmit direct light and reflected light upwardly, one of said lower parts having an upwardly and outwardly flaring portion beyond the periphery of the cover plate for screening the cover plate at angles below the horizontal, means for supporting the stem and cover plate in position relative to the lamp 85 bulb, 90 said means including frame members extending from above the lamp bulb down alongside the bulb, and a detachable connection between the stem and frame members.

3. An inclosed indirect lighting unit, comprising a pendant lamp bulb, a pendant axially disposed stem below the lamp bulb, a diffusing bowl removably secured to the stem, an outwardly and upwardly flaring reflector disposed between the lamp bulb and the lower bowl which conceals the reflector and provides the unit with its lower 105 ornamental appearance, an inverted dished translucent cover plate above the lamp and reflector and engaging at its periphery one of said lower parts to form a closed body about the lamp bulb and transmit direct light and reflected light up- 110 wardly, one of said lower parts having an upwardly and outwardly flaring portion beyond the periphery of the cover plate for screening the cover plate at angles below the horizontal, and means for supporting the stem and cover plate in 115 position relative to the lamp bulb.

4. An inclosed indirect lighting unit, comprising a pendant lamp bulb, a pendant axially disposed stem below the lamp bulb, a diffusing bowl removably secured to the stem, an outwardly and upwardly flaring reflector disposed between the lamp bulb and the lower bowl which conceals the reflector and provides the unit with its lower 120 ornamental appearance, an inverted dished translucent cover plate above the lamp and reflector and engaging at its periphery one of said lower parts to form a closed body about the lamp bulb and transmit direct light and reflected light upwardly, one of said lower parts having an upwardly and outwardly flaring portion beyond the 125 periphery of the cover plate for screening the cover plate at angles below the horizontal, means for supporting the stem and cover plate in position relative to the lamp bulb, the center of the reflector being open to permit light to pass downwardly, and a small reflector to receive such light 130 and scatter it about in the bowl.

5. A lighting unit having a pendant lamp bulb, a frame about the lamp bulb, a downwardly extending axial stem carried by the frame, a lower 145 ornamental cover member removably secured to the stem and extending upwardly and outwardly, and an upwardly and outwardly flaring reflector supported from the frame and disposed between the lamp bulb and lower cover member which 150

conceals the same and provides the lighting unit with its lower ornamental appearance.

6. An inclosed indirect lighting unit having a pendant lamp bulb, a frame about the lamp bulb, 5 downwardly extending axial stem carried by the frame, a lower ornamental cover member removably secured to the stem and extending upwardly and outwardly, an upwardly and outwardly flaring reflector supported from the frame and disposed between the lamp bulb and lower cover member which conceals the same and provides the lighting unit with its lower ornamental appearance, and an upper translucent cover member supported by the upper part of the frame and 15 having its edge in engagement with one of the parts carried by the frame to steady the same and enclose the lamp bulb.

7. A lighting unit having a pendant lamp bulb, a frame about the lamp bulb, downwardly extending axial stem carried by the frame, a lower ornamental cover member removably secured to the stem and extending upwardly and outwardly, and an upwardly and outwardly flaring reflector supported from the frame and disposed between the lamp bulb and the lower cover member which conceals the same and provides the lighting unit with its lower ornamental appearance, the frame being jointed so as to permit lateral movement of a part thereof for lamp bulb renewal.

8. A lighting unit having a pendant lamp bulb, a frame about the lamp bulb, downwardly extending axial stem carried by the frame, a diffusing glass bowl removably secured to the stem and extending upwardly and outwardly, and an upwardly and outwardly flaring reflector supported from the frame and disposed between the lamp bulb and lower cover member which conceals the same and provides the lighting unit with its lower ornamental appearance, the reflector being perforated to permit passage of light for illuminating the bowl.

9. An inclosed indirect lighting unit having a pendant lamp bulb, a frame about the lamp bulb, a downwardly extending stem carried by the frame, an upper translucent glass cover member supported by the upper part of the frame, a lower diffusing glass bowl removably secured to the stem, an outwardly and upwardly flaring reflector interposed between the lamp bulb and lower bowl, 50 the reflector having a light transmitting opening to permit light to pass to the interior of the bowl for diffusion thereby, and a rigid member between the edges of the bowl and cover member to provide a totally enclosed unit and steady the bowl relative to the cover member.

10. An inclosed indirect lighting unit having a pendant lamp bulb, a frame about the lamp bulb, a downwardly extending stem carried by the frame, an upper translucent glass cover member supported by the upper part of the frame, a lower diffusing glass bowl removably secured to the stem, an outwardly and upwardly flaring reflector interposed between the lamp bulb and lower bowl, the reflector having a central light transmitting 65 opening to permit light to pass downwardly, a small reflector to receive such light and scatter it about inside the bowl for diffusion thereby, and a rigid member between the edges of the bowl and cover member to provide a totally enclosed unit and steady the bowl relative to the cover member.

11. An inclosed indirect lighting unit having a pendant lamp bulb, a frame about the lamp bulb, a downwardly extending stem carried by the frame, an upper translucent glass cover member supported by the upper part of the frame, a lower

diffusing glass bowl removably secured to the stem, and an outwardly and upwardly flaring sheet metal stamping having a central reflecting zone and an outer portion which extends outwardly between the two glass parts and is in contact with both such parts, said outer portion also screening the glass cover at angles below the horizontal.

12. An inclosed indirect lighting unit having a pendant lamp bulb, a frame about the lamp bulb, a downwardly extending stem carried by the frame, an outwardly and upwardly flaring sheet metal reflector secured to the frame the center of the reflector being close underneath the bulb, and having its periphery adjacent the edge of the glass cover member, and a lower reflector cover detachably secured to the stem to permit lamp bulb renewal, the reflector cover concealing the reflector, engaging the edge of the glass cover member and enclosing the unit.

13. An inclosed indirect lighting unit comprising a pendant lamp socket, a lamp bulb in the socket, a frame detachably secured adjacent the socket, the frame having an upper portion extending downwardly about the lamp bulb, and having a lower movable portion below the lamp bulb and hingedly secured to the upper portion so that it may be swung to one side to permit lamp bulb renewal, a downwardly extending threaded stem secured to the movable portion of the frame, an upwardly acting opaque reflector disposed below the frame for intercepting downwardly directed light and reflecting it upwardly, means for supporting the reflector from the stem, an ornamental lower cover carried by the stem below the reflector for concealing the reflector, and an upper translucent cover for transmitting the direct and upwardly reflected light, the upper cover and reflector having substantially the same outside diameter, the upper cover being in engagement with one of the lower parts to provide a totally enclosed unit.

14. In a lighting fixture, a socket cover, a socket therein adapted to carry a lamp bulb, a ring large enough to receive the neck of the lamp bulb and substantially smaller than the lower end of the socket cover, means to secure the ring within said lower end of the socket cover, and a frame carried by the ring, the frame comprising two fixed depending upper members adapted to admit the upper part of the lamp bulb and a lower semi-circular member adapted to extend underneath the lamp bulb, and means to hinge the lower member to the two upper members so that the lower member may be swung to one side to permit lamp bulb renewal.

15. In a lighting fixture, a socket cover, a socket therein adapted to carry a lamp bulb, a ring large enough to receive the neck of the lamp bulb and substantially smaller than the lower end of the socket cover, means to secure the ring within said lower end of the socket cover, and a frame carried by the ring, the frame comprising two fixed depending upper members adapted to admit the upper part of the lamp bulb and a lower semi-circular member adapted to extend underneath the lamp bulb, said frame members being in the form of sheet metal straps presenting their thin edges to the light rays, and links between the members for hinging them together so that the lower member may be swung to one side to permit lamp bulb renewal.

16. In a lighting fixture, a socket cover, a socket therein adapted to carry a lamp bulb, a ring large

- enough to receive the neck of the lamp bulb and substantially smaller than the lower end of the socket cover, means to secure the ring within said lower end at the socket 5 cover, a frame carried by the ring, the frame comprising two fixed depending upper members adapted to admit the upper part of the lamp bulb and a lower semi-circular member adapted to extend underneath the lamp bulb, and 10 means to hinge the lower member to the two upper members so that the lower member may be swung to one side to permit lamp bulb renewal, and a glass cover member having its inner edge between the ring and socket cover.
- 15 17. In a lighting fixture, a socket cover, a socket therein adapted to carry a lamp bulb, a ring large enough to receive the neck of the lamp bulb and substantially smaller than the lower end of the socket cover, means to secure the ring within 20 said lower end of the socket cover, a frame carried by the ring, the frame comprising two fixed depending upper members adapted to admit the upper part of the lamp bulb and a lower semi-circular member adapted to extend underneath the lamp bulb, means to hinge the lower member to the two upper members so that the lower member may be swung to one side to permit lamp bulb renewal, a glass cover member having its inner edge between the ring and socket cover, 25 and a reflector removably supported by the lower frame member, the reflector being underneath the lamp bulb and extending substantially to the outer lower edge of the cover member.
18. In a lighting fixture, a socket cover, a socket 30 therein adapted to carry a lamp bulb, a ring large enough to receive the neck of the lamp bulb and substantially smaller than the lower end of the socket cover, means to secure the ring within said lower end of the socket cover, a frame carried 35 by the ring, the frame comprising two fixed depending upper members adapted to admit the upper part of the lamp bulb and a lower semi-circular member adapted to extend underneath the lamp bulb, means to hinge the lower member to the two upper members so that the lower member 40 may be swung to one side to permit lamp bulb renewal, a reflector underneath the lamp bulb and frame, and means to support it from the frame, and a light transmitting cover member carried by 45 the frame above the lamp and having its outer edge adjacent the outer edge of the reflector.
19. In an inclosed indirect lighting unit, a pendant lamp bulb, a frame supported from above the lamp bulb and extending downwardly to be 50 underneath the lamp bulb, the frame being jointed so as to permit lateral movement of the lower part thereof for lamp bulb renewal, a downwardly extending axial stem carried by the lower part of the frame, a light transmitting cover plate supported from the upper part of the frame, a reflector below the lamp bulb, the reflector having 55 an unornamental shape designed for light redistribution upwardly in a predetermined manner and extending substantially to the outer edge of the cover plate, a lower cover member below the reflector for concealing the reflector, and means for supporting the reflector and the lower cover member from the stem.
- 60 20. In an inclosed indirect lighting unit, a pendant lamp bulb, a frame supported from above the lamp bulb and extending downwardly to be underneath the lamp bulb, the frame being jointed so as to permit lateral movement of the lower part thereof for lamp bulb renewal, a down- 65
- wardly extending axial stem carried by the lower part of the frame, a light transmitting cover plate supported from the upper part of the frame, a reflector below the lamp bulb, the reflector having a central spherical portion and an outer shallow concave portion extending substantially to the outer edge of the cover plate, a lower cover member below the reflector for concealing the reflector, and means for supporting the reflector and the lower cover member from the stem. 70
21. In an inclosed indirect lighting unit, a pendant lamp bulb, a frame supported from above the lamp bulb and extending downwardly to be underneath the lamp bulb, the frame being jointed so as to permit lateral movement of the lower part thereof for lamp bulb renewal, a downwardly extending axial stem carried by the lower part of the frame, a light transmitting cover plate supported from the upper part of the frame, a reflector below the lamp bulb, the reflector having a central spherical portion and an outer shallow concave portion extending substantially to the outer edge of the cover plate and being perforated to allow some light to escape downwardly, a lower diffusing cover member 75 below the reflector for concealing the reflector and receiving the light passing through the perforations, and means for supporting the reflector and the lower cover member from the stem. 80
22. In an inclosed indirect lighting unit, a pendant lamp bulb, a frame supported from above the lamp bulb and extending downwardly to be underneath the lamp bulb, the frame being jointed so as to permit lateral movement of the lower part thereof for lamp bulb renewal, a downwardly extending axial stem carried by the lower part of the frame, a light transmitting cover plate supported from the upper part of the frame, a reflector below the lamp bulb, the reflector having a central spherical portion and an outer shallow concave portion extending substantially to the outer edge of the concave plate, a lower cover member below the reflector for concealing the reflector, means for supporting the reflector and the lower cover member from the stem, and an opaque screening member extending outwardly and upwardly from the lower edge of the cover plate and supported from the stem. 85
23. An inclosed lighting unit comprising a pendant lamp bulb, a ring-like support about the neck of the lamp bulb, a translucent glass cover plate carried by the ring-like support, frame members carried by the ring-like support and extending downwardly alongside the lamp bulb, a sheet metal reflector having a central substantially spherical portion and a peripheral shallow dished portion extending substantially out to the edge of the glass cover plate, detachable connections between the frame members and reflector, an axially disposed stem extending downwardly from the reflector, and a lower mask detachably carried by the stem, the mask concealing the reflector and being in engagement with the lower edge of the cover plate. 90
24. An inclosed lighting unit comprising a pendant lamp bulb, a ring-like support about the neck of the lamp bulb, a translucent glass cover plate carried by the ring-like support, two frame members carried by the ring-like support and extending downwardly alongside the lamp bulb, a sheet metal reflector having a central substantially spherical portion and a peripheral shallow dished portion extending substan- 95

tially out to the edge of the glass cover plate, detachable connections between the frame members and reflector said connections being such that, when one only is detached, the reflector 5 may be suspended in an oblique position by the other, the upper edge of the reflector passing

up inside the cover plate, an axially disposed stem extending downwardly from the reflector, and a lower mask detachably carried by the stem, the mask concealing the reflector and being in engagement with the lower edge of the cover plate. 80
